FEED FOR WRAPPING MACHINES

Elmer F. Mertis, Brooklyn, N. Y., assignor to
 American Machine & Foundry Company, a corporation of New Jersey

Application May 31, 1934, Serial No. 728,409

7 Claims. (Cl. 93—2)

This invention relates to an improvement in wrapping machines and has for its main object to provide a device for controlling the feed of the wrapping material so as to enable the attendant 5 of the machine to select which one of three kinds of packages to produce, viz. "tight wrapped", "moderately tight wrapped" or "loose wrapped". While the invention is illustrated in conjunction with bread wrapping machines, its usefulness is 10 not limited thereto as it may be used with any type of wrapping machine.

In Patent No. 1,805,677, granted May 19, 1931, on the application of F. R. Schmitt, there is disclosed a device for producing a loosely wrapped 15 package, and the principle involved in that patent is embodied in the present invention with the addition of means for controlling its operation so as to enable the attendant, by the simple manipulation of a slidable shaft, to instantly adjust the machine so as to produce the type of 20 package desired.

In the accompanying drawing which forms a part of this specification and in which like characters of reference indicate the same or like 25 parts,

Fig. 1 is a side elevation of the device illustrating the invention, showing the same adjusted to produce a "loose wrapped" package;

Fig. 2 is a partial end elevation of Fig. 1; 30 Fig. 3 is a detail cross section showing the arrangement of the gear train for changing into different conditions of wrapping;

Fig. 4 is a sectional side elevation showing an article in two different stages during the wrapping operation.

In carrying the invention into effect there is provided article wrapping mechanism operating to partially enfold an article in a web of wrapping material, a pair of feed rollers coacting to engage the web and exert a moderate resistance to its passage therebetween in order to produce an "average wrapped" package, and means operative to drive one of said rollers either toward the article being wrapped to feed an additional 40 length of material, or away from said article to exert a drag on the web so that a "loose wrapped" or "tight wrapped" package will be produced respectively. In the best constructions contemplated there is provided an oscillatory frame carrying one of the feed rollers and periodically operating to swing the same into position to coact with the other feed roller to exert a moderate resistance to the passage of the web therebetween, and said means includes a driven shaft, a slid- 45 able shaft movable into engagement with the

driven shaft to be in turn driven directly therefrom, one of the feed rollers being driven from the slidable shaft, whereby the feed rollers will exert a drag on the web when the shafts are coupled and thus produce a "tight wrapped" package, a gear fast to the driven shaft, a pin in the slidable shaft, a gear loose on the slidable shaft and constantly driven from the gear on the driven shaft and provided with a notch adapted to receive the pin when the slidable shaft is drawn out of coupling engagement with the driven shaft in order to feed the additional length of web for loose wrapping of the article. These various means and parts may be widely varied in construction within the scope of the claims for 5 the particular device selected to illustrate the invention is but one of many possible concrete embodiments of the same. The invention, therefore, is not to be restricted to the specific construction shown and described.

Referring to Figs. 1, 2 and 3 of the drawing the endless pusher chain 11 of the wrapping machine runs over a sprocket 12 fast to the shaft 13 journaled in a bearing at one end of the gear housing 14. The latter is suspended from the 15 main frame WM of the machine, which is of the type disclosed in the patent to H. Y. Armstrong, No. 1,626,379, granted April 26, 1927. In the bearing at the other end of gear housing 14 is a shaft 15 on the outer end of which is mounted 20 a sprocket 16 which through chain 17 drives sprocket 18 on the feed roller 19.

Bevel gear 20 attached to the inner end of shaft 13 drives a bevel gear 21 which is free to rotate on stud 21a. Gear 21 meshes with a 25 bevel gear 22 loose on shaft 15 slidably mounted in gear housing 14. When the gear train is in the neutral position as shown in Fig. 3, the gear 22 rotates idly on shaft 15, but if shaft 15 is pushed in so that its tongue 15a engages slot 13a in shaft 13 the rotation of sprocket 12 will be transmitted directly through shafts 13 and 15 to sprocket 16 thereby driving the feed roller 19 in a direction to effect tight wrapping of the loaf, as will be presently described. If shaft 15 35 is pulled out so that pin 15b thereof engages notch 22a in gear 22, the rotation of sprocket 12 will be transmitted through shaft 13, gears 20, 21 and 22 and shaft 15 to drive the sprocket 16 in the opposite direction to effect loose wrapping of the loaf, as will be presently described. The hub of sprocket 16 is held against the gear housing 14 by means of a clip collar 16a thereon engaging the clip ring 14a fastened to the gear housing 40 and the sprocket 16 is driven from the shaft 50 45 55

- 15 by means of a cross pin 15c engaging notches 16d in the hub of the sprocket 16. The shaft 15 is locked against axial movement by a spring latch consisting of a ball 16b disposed in a recess in the 5 hub of sprocket 16 and pressed by a coil spring 16c into one of three depressions 15d formed in shaft 15 corresponding to the different positions of shaft 15, for tight, loose, or moderately tight wrapping.
- 10 Roller 19 is journaled in bearings 23a of oscillating frame 23 which is fulcrumed on rod 24 and periodically actuated by connecting rod 25 operated from a cam or by other suitable means (not shown) to swing the feed roller 19 in and out 15 of position to coat the feed roller 26 on swinging lifter table 27, as shown in dotted lines in Fig. 4, while the lifter table is in a raised position.

Referring now to Fig. 1, only, of the drawing, an article in the present case a loaf of bread, 20 is shown in a position corresponding to that shown in Fig. 1 of the drawing of the above mentioned Armstrong patent, the loaf being shown to be partially enfolded in a wrapper. It may be noted that the loaf is partially enwrapped by pushing it from the infeed runway into the end portion of a web of wrapping material and onto the lifter table while the latter is in its lower position, the movement of the loaf serving to fold the web about three sides thereof and pull 25 off the web from the roll of wrapping material (not shown). Since the web is pulled against the resistance of the roll of wrapping material and the web guiding means (not shown), it is drawn quite tightly about the loaf. The web is 30 pressed against the top of the loaf by a spring finger 21a supported on an upstanding rod of the lifter table 27. As the lifter table swings to its upper position, it pulls off more wrapping material from the roll, leaving the web W in the 35 dotted position shown in Fig. 1. Up to this time the wrapping mechanism has pulled off a length of material just sufficient to wrap the loaf to produce a "moderately tight wrapped" or "average wrapped" package if the slidable shaft 15 is 40 left in the neutral position.

When the lifter table is swung into the raised position shown in Fig. 1 the feed roller 19 pinches the wrapping material W against feed roller 26, and if the shaft 15 has been pulled out the roller 50 19 will rotate anti-clockwise as indicated by the arrow and thus coat with the roller 26 to feed an additional length of wrapping material for loose wrapping of the article. After a sufficient length of web has been fed by the rollers 19 and 55 26 the loaf is advanced from the lifter table 27 onto the sealing table 28 by means of a pusher on the traveling chain 11. During this advance the web is cut by a knife 29 carried by blocks 30 pivoted on frame 23 and actuated by a cam rod 60 31 from a cam (not shown) to sever the web on the ledger plate 32, and the frame 23 is then retracted with the roller 19. As an article is advanced over the sealing table this excess material is wiped under its bottom as roller 19 has been 65 swung away, from the roller 26; accordingly, no tension is applied to the wrapper during the final stages of the operation of enfolding the loaf in the wrapper, and a "loose wrapped" package will result after the loosely enwrapped loaf is 70 subjected to the usual end folding and sealing operations.

If instead of pulling out shaft 15, it is pushed in so as to be coupled directly with shaft 13 the drive of sprocket 16 will be reversed and, as 75 a result, roller 19 will rotate in the opposite direc-

tion from the case just described, and the wrapping material W will be subjected to the drag resulting from being pinched between the roller 19 and the roller 26 on the lifter table 27 as indicated (by dotted lines) in Figs. 1 and 4, and the final result would be a "tight wrapped" package. 5

Should the shaft 15 be left in a neutral position, as shown in Fig. 3, no power would be transmitted to sprocket 16 and as the roller 19 would not be rotated in either direction, the 10 wrapping material would pass, with only moderate resistance, between rollers 19 and 26 and the result would be a "moderately tight wrapped" or "average wrapped" package.

What is claimed is:

1. The combination with article wrapping mechanism operating to partially enfold an article in the leading end of a web of wrapping material, of a pair of feed rollers coacting to engage the web and exert a moderate resistance 20 to its passage therebetween in order to produce an "average wrapped" package, and means operative to drive one of said rollers either toward the article being wrapped to feed an additional length of wrapping material, or away from said article to exert a drag on the web, whereby a "loose wrapped" or "tight wrapped" package will be produced respectively.

2. The combination with article wrapping mechanism operating to partially enfold an article in the leading end of a web of wrapping material, of a pair of feed rollers coacting to engage the web and exert a moderate resistance 30 to its passage therebetween in order to produce an "average wrapped" package, and means operative to drive one of said rollers either toward the article being wrapped to feed an additional length of wrapping material, or away from said article to exert a drag on the web, whereby a "loose wrapped" or "tight wrapped" package will be 40 produced respectively, and an oscillatory frame carrying one of said rollers and periodically operating to swing the same into position to coat with the other feed roller to exert a moderate resistance to the passage of the web therebetween.

3. The combination with article wrapping mechanism operating to partially enfold an article in the leading end of a web of wrapping material, of a pair of feed rollers coacting to engage the web and exert a moderate resistance 50 to its passage therebetween in order to produce an "average wrapped" package, and means operative to drive one of said rollers either toward the article being wrapped to feed an additional length of wrapping material, or away from said article to exert a drag on the web, whereby a "loose wrapped" or "tight wrapped" package will be produced respectively, an oscillatory frame carrying one of said rollers and periodically operating to swing the same into position to coat with the 60 other feed roller to exert a moderate resistance to the passage of the web therebetween, and a knife mounted on said frame for severing the web.

4. The combination with article wrapping mechanism operating to partially enfold an article in the leading end of a web of wrapping material, of a pair of feed rollers coacting to engage the web and exert a moderate resistance 65 to its passage therebetween in order to produce an "average wrapped" package, and means operative to drive one of said rollers either toward the article being wrapped to feed an additional length of wrapping material, or away from said article to exert a drag on the web, whereby a "loose wrapped" or "tight wrapped" package will be pro- 70 75 80 85 90 95

- duced respectively, said means including a driven shaft, a slidable shaft movable into engagement with said driven shaft to be in turn driven directly therefrom, one of said feed rollers being driven 5 from said slidable shaft, whereby the feed rollers will exert a drag on the web when said shafts are coupled and thus produce a "tight wrapped" package, a gear fast to said driven shaft, a pin in said slidable shaft, a gear loose on said slidable 10 shaft and constantly driven from the gear on the driven shaft and provided with a notch adapted to receive said pin when the slidable shaft is drawn out of coupling engagement with said driven shaft in order to cause the feed rollers to 15 feed the additional length of web for loose wrapping of the article, said slidable shaft being movable into a neutral position in which it is uncoupled from the driven shaft and its pin is clear of said notch.
- 20 5. The combination with a pair of web feeding rollers, of a driven shaft, a slidable shaft movable into engagement with said driven shaft to be in turn driven directly therefrom, one of said rollers being driven from said slidable shaft, whereby 25 said rollers will exert a drag on the web when said shafts are coupled, a gear fast to said driven shaft, a pin fixed in said slidable shaft, a gear loosely mounted on said slidable shaft and constantly driven from the gear on the driven shaft 30 and provided with a notch adapted to receive said pin when the slidable shaft is drawn out of coupling engagement with said driven shaft to cause said rollers to feed the web, said slidable shaft being movable into a neutral position in
- which it is uncoupled from the driven shaft and its pin is clear of said notch.
6. The combination with a pair of web feeding rollers, of a driven shaft, a slidable shaft movable into engagement with said driven shaft to be in turn driven directly therefrom, one of said rollers being driven from said slidable shaft, whereby 5 said rollers will exert a drag on the web when said shafts are coupled, a gear fast to said driven shaft, a pin fixed in said slidable shaft, a gear 10 loosely mounted on said slidable shaft and constantly driven from the gear on the driven shaft and provided with a notch adapted to receive said pin when the slidable shaft is drawn out of coupling engagement with said driven shaft to 15 cause said rollers to feed the web, said slidable shaft being movable into a neutral position in which it is uncoupled from the driven shaft and its pin is clear of said notch, and an oscillatory 20 frame carrying one of said feed rollers and periodically operating to swing the same into position to coat with the other feed roller to feed the web.
7. The combination with article wrapping mechanism operating to partially enfold an article in wrapping material, of a pair of feed rollers coating to engage the web and exert a moderate resistance to its passage therebetween in order to produce an "average wrapped" package, and means operative to drive one of said 25 rollers, and a manually operable control mechanism coating with said means to vary the direction of rotation of the driven roller.

ELMER F. MERTIS.
